United States Patent Office

Des. 192,856
Patented May 22, 1962

192,856

KEY RING

George W. McKee, 5184 Priscilla Drive, Bethel Park, Pa.

Filed Nov. 8, 1960, Ser. No. 62,765

Term of patent 3½ years

(Cl. D17—14)

Fig. 1.

Fig. 2.

FIG. 1 shows a top plan view of a key ring showing my new design, the side opposite the pendant being substantially plain and flat; and

FIG. 2 shows a side elevational view thereof.

I claim:

The ornamental design for a key ring, as shown.
